UNITED STATES PATENT OFFICE

ARTHUR B. ELLERY, OF AKRON, OHIO

DOOR-LATCHING MECHANISM

Application filed January 6, 1928. Serial No. 244,845.

This invention relates to door latching mechanism, and while it is applicable to doors of various kinds, it is particularly designed and intended for automobile doors. The object of the invention is to improve upon door latches of the type in which there is provided a sliding latch carried upon the door and designed to engage a keeper in the frame surrounding the door.

10 Latches of this type are apt to develop squeaks due to the fact that the latch rubs against the side of the keeper while the automobile is in motion, and it is for the purpose of eliminating this objectionable squeaking

15 that the present design of latch has been made.

In the drawings in which the preferred form of the invention is shown, the details of the door and latch operating mechanism 20 are non-essential and are shown merely as illustrative of one method of mounting the improved latch mechanism.

In the drawings:

Figure 1 is a side elevation of a door with 25 the improved latching mechanism shown thereon;

Figure 2 is a section on the line 2—2 of Figure 1;

Figures 3 and 4 are detail views of the 30 latch.

In the drawings, the door is indicated by the numeral 1 and the frame by the numeral 2. In the edge of the frame is attached the usual striker plate or keeper 5 which is provided with the plane surfaces 6 against one or the other of which the movable latch 7 bears. This latch is operated by the usual handle and operating mechanism 8.

The latch 7 is provided with a vertical face 40 9 which, when the door is closed, contacts with the vertical face 6 on the striker plate. It is due to the rubbing of these two vertical faces that squeaks are developed.

My invention consists in providing a suitable lubricating means by which a lubricant 45 will be supplied to the contacting faces of the latch and the keeper. Different forms of devices for this purpose may be developed, the particular form illustrated herein comprising a reservoir for oil from which it

seeps out onto the face of the latch. This reservoir or well is obtained by forming a large hole 10 vertically in the latch, from which smaller openings 11 communicate with the vertical face of the latch. The hole 10 55 is filled with an absorbent material, preferably cotton, fibres of which may protrude through the openings 11. The cotton is saturated with oil which seeps through the openings and keeps a thin film of oil on the face of the latch. In this manner the contacting surfaces of the latch and keeper are lubricated and the objectionable squeaking is obviated.

What is claimed is:

1. In a door latching mechanism, the combination of a door and a frame, a sliding latch in the door and a keeper in the frame, the latch and keeper having vertical faces in contact when the door is closed, and having a vertical well in the latch, said well being open at the top and said latch being formed with passageways leading from the well to the vertical face of the latch, and an absorbent packing in the well.

2. In a holding device for vehicle doors, the combination of two members, one of which constitutes a relatively fixed striker plate and the other a horizontally reciprocable latch, means for mounting one of said members on the door jamb and the other on the free edge of the door, said members having vertical surfaces which abut each other when the door is closed and latched, and means contained within one of said members for applying a thin film of lubricant directly to the abutting surface of the other member when the door is latched.

ARTHUR B. ELLERY.
